UNITED STATES PATENT OFFICE.

JOHN MILTON KELLY, OF WHEELING, WEST VIRGINIA, ASSIGNOR OF ONE-HALF TO HENRY MORRIS, OF SAME PLACE.

LETTER AND BILL FILE.

SPECIFICATION forming part of Letters Patent No. 372,983, dated November 8, 1887.

Application filed April 1, 1887. Serial No. 233,293. (No model.)

To all whom it may concern:

Be it known that I, JOHN MILTON KELLY, a resident of the city of Wheeling, in the county of Ohio and State of West Virginia, have invented certain new and useful Improvements in Letter and Bill Files; and I do hereby declare that the following is a full, clear, and exact description of the invention, which will enable others skilled in the art to which it applies to make and use the same, reference being had to the accompanying drawings, and to letters of reference marked thereon, which form a part of this specification.

My invention relates to that class of letter and bill files that are made in the form of a book cover or binder, having a series of hooks secured to the inside of the cover, upon which the papers are hung and retained in place.

The object of my invention is to provide a file in which the hooks are fastened to a detachable plate or rack, made removable, in order that the same, together with the papers thereon, may be removed and filed away and another rack substituted in its place, thus obviating the necessity of procuring another binder when the one in use is full of papers.

In the drawings, Figure 1 is an inside view of the file; Fig. 2, a transverse section.

The letter A designates a metallic spring back or case, made preferably of sheet metal, containing the hook-rack and clamping-plate for holding the papers in place.

B' are the covers attached to the back in the usual manner, and may be of paper-board or other suitable material.

C is a hook-rack consisting of an angle iron or plate of sheet metal, to which is attached a series of hooks, D. This plate is secured in position on the inside of the case by a small ring-bolt, E, which passes through an opening in the side of the case and through the plate on the inside, having prongs a a, adapted to being opened outward and bent back against the side of the plate in the manner of a paper-fastener. Attached to the bolt on the outside of

the case is a ring, F, by means of which the file can be hung upon the wall for convenience and ready reference.

G is a spring-actuated clamping-plate for holding the papers in place on the hook-rack. 50 One edge of the plate is secured to a rod, c, which passes through the case and is pivoted at each end to the ends of the case. This rod is curved from a straight line at d d to form cams for the springs to press against to hold 55 the clamping-plate either against or away from the hook-rack, as desired.

b b are the springs securely fastened in position near the ends of the case A. These springs, aside from holding the clamping-plate, 60 also abut against the hook-rack C, and serve also to hold it in place in conjunction with the fastening device E in the center of the plate.

Having described my invention, what I claim, and desire to secure by Letters Patent 65 of the United States, is—

1. In a letter and bill file, a removable hook-rack consisting of an angle-plate, C, having hooks D secured thereto, substantially as described.

2. The combination, with the metallic back A, of the removable hook-rack C, and fastening device E, having a ring, F, substantially as and for the purpose set forth. 70

3. The combination of the metallic back A, 75 covers B B', removable hook-rack C, fastening device E, ring F, springs b b, and clamping-plate G, substantially as and for the purpose set forth.

4. In combination with the angle-plate C, 80 having hooks D, the clamping-plate G, and spring b, bearing upon each end thereof, substantially as described.

In testimony that I do claim the foregoing as my own I hereby affix my signature in presence of two witnesses.

JOHN MILTON KELLY.
